(57) **CLAIM**

The ornamental design for a support for electronic device, as shown and described.

DESCRIPTION

FIG. 1 is a perspective view of a support for electronic device embodying the new design;

FIG. 2 is another perspective view of the support for electronic device;

FIG. 3 is a front view thereof;

FIG. 4 is a back view thereof;

FIG. 5 is a side view thereof;

FIG. 6 is another side view thereof;

FIG. 7 is a top view thereof;

FIG. 8 is a bottom view thereof;

FIG. 9 is a perspective view of the support for electronic device in a folded state;

FIG. 10 is a perspective view of the support for electronic device in a state of use; and,

FIG. 11 is another perspective view of the support for electronic device in a state of use.

In the drawings, the broken line showing of a mobile device is for the purpose of illustrating environmental structure and forms no part of the claimed design.

1 Claim, 11 Drawing Sheets
